UNITED STATES PATENT OFFICE.

JULIUS T. ROSENHEIMER, OF NEW YORK, N. Y.

DESIGN FOR A NEEDLE-CASE.

SPECIFICATION forming part of Design No. 35,704, dated February 11, 1902.

Application filed December 24, 1901. Serial No. 87,134. Term of patent 3½ years.

To all whom it may concern:

Be it known that I, JULIUS T. ROSENHEIMER, a citizen of the United States, and a resident of New York city, county and State of New York, have invented a new and original Design for Needle-Cases, of which the following is a specification, reference being had to the accompanying drawings, in which—

Figure 1 is a perspective view of a needle-case, showing my design; and Fig. 2 is a longitudinal section on line 2 2, Fig. 1.

As shown in the drawings, the leading feature of the design consists of a needle-case A, having a number of obliquely-arranged flaps 15 a. Each flap a has a circular opening a', a

convex upper end a², and a concave lower end a³, flanged by beveled edges a⁴. Above and below the flaps a are shown oblong panels b, having parallel ridges b'.

What I claim is—

The design for a needle-case, substantially as herein shown and described.

Signed by me at New York city, county and State of New York, this 23d day of December, 1901.

JULIUS T. ROSENHEIMER.
